(57) **CLAIM**

The ornamental design for a toy foam stick, as shown and described.

DESCRIPTION

FIG. 1 is a reduced perspective environmental view of the embodiment of the present invention;

FIG. 2 is a reduced perspective environmental view of an alternative embodiment of the present invention;

FIG. 3 is an enlarged perspective view of the embodiment of the present invention;

FIG. 4 is an enlarged perspective view of an alternative embodiment of the present invention;

FIG. 5 is a side view of the embodiment of the present invention shown rotated slightly clockwise about the top end;

FIG. 6 is a side view of the embodiment of the present invention shown rotated slightly clockwise from the previous figure;

FIG. 7 is a side view of the embodiment of the present invention shown rotated slightly clockwise from the previous figure;

FIG. 8 is a side view of the embodiment of the present invention shown rotated slightly clockwise from the previous figure;

FIG. 9 is a side view of the embodiment of the present invention shown rotated slightly clockwise from the previous figure;

FIG. 10 is a side view of the embodiment of the present invention shown rotated slightly clockwise from the previous figure;

FIG. 11 is a side view of an alternative embodiment of the present invention shown rotated slightly clockwise about the top end;

FIG. 12 is a side view of an alternative embodiment of the present invention shown rotated slightly clockwise from the previous figure;

FIG. 13 is a side view of an alternative embodiment of the present invention shown rotated slightly clockwise from the previous figure;

FIG. 14 is a side view of an alternative embodiment of the present invention shown rotated slightly clockwise from the previous figure;

FIG. 15 is a side view of an alternative embodiment of the present invention shown rotated slightly clockwise from the previous figure; and,

FIG. 16 is a side view of an alternative embodiment of the present invention shown rotated slightly clockwise from the previous figure.

The broken lines are environmental and form no part of the claimed design.
